(57) CLAIM

The ornamental design for a wellness spa capsule, as shown and described.

DESCRIPTION

FIG. 1 is a rear and right side perspective view of a wellness spa capsule embodying our new design;

FIG. 2 is a top plan view thereof;

FIG. 3 is a front elevational view thereof;

FIG. 4 is a rear elevated view thereof;

FIG. 5 is a left side elevational view thereof;

FIG. 6 is a right side elevational view thereof; and,

FIG. 7 is a bottom plan view thereof.

The broken lines are for illustrative purposes only and form no part of the claimed design.
